UNITED STATES PATENT OFFICE.

CHARLES W. SCHWARTZ, JR., OF PHILADELPHIA, PENNSYLVANIA,
ASSIGNOR TO THE PHILADELPHIA TEXTILE MACHINERY COMPANY, OF PHILADELPHIA, PENNSYLVANIA, A CORPORATION OF PENNSYLVANIA.

DRIER.

No. 842,025.

Specification of Letters Patent.

Patented Jan. 22, 1907.

Application filed April 25, 1906. Serial No. 313,648.

To all whom it may concern:

Be it known that I, CHARLES W. SCHWARTZ, Jr., a citizen of the United States, residing in Philadelphia, Pennsylvania, have invented 5 certain improvements in Driers, of which the following is a specification.

My invention relates to that class of drying-machines in which a horizontal fan is located at the top of the drying-chamber for 10 circulating the air through the said chamber and through heating-chambers at the sides of the drying-chamber.

The present machine illustrates a construction in which the fan directs the current 15 of air downwardly in said chamber, the volume of air then rising through the heating-chambers, entering the top of the drying-chamber, and being again forced downwardly therein. It will be understood that the direction of the air may be reversed, if desired.

The object of my invention is to prevent the heating and drying out of the lubricant in the bearings for the vertical shaft which carries the horizontal fan.

25 The invention also relates to the particular construction of the supports for the said vertical shaft.

In the accompanying drawings, Figure 1 shows a transverse vertical section of sufficient 30 of a drying-machine of the character to which my invention relates to illustrate said invention, and Fig. 2 is an enlarged section of part of the device.

In Fig. 1 of the drawings, 1 represents the 35 outer casing of the machine, and 2 a vertical shaft free to turn in bearings 3 and 4, carried, respectively, by cross-beams 5 and 6 of the structure, said shaft being provided at its lower end with a rotary fan 7, having a solid 40 central portion 8 of considerable area, usually about one-third of the diameter of the fan.

The structure contains a drying-chamber 9 and heating-chambers 10 at each side of the same, provided with steam-coils or other 45 available air-heating devices, relatively short internal partitions 11 causing the air to follow the courses indicated by the arrows when the fan 7 is properly rotated.

Surrounding a central opening in the top 50 of the casing 1 and depending from the latter is a cylindrical shield or guard 12, which is of a diameter substantially coincident with that of the imperforate center 8 of the rotary fan,

the lower edge of said cylindrical shield or guard 12 approaching closely to the upper 55 surface of the closed center 8 of the fan. By reason of this construction the currents of hot air circulating in the upper portion of the drying-chamber 9 cannot gain access to the shaft 2 and its bearings. Hence the heating of the 60 latter and the drying out of the lubricant therefor are effectually prevented, especially when the space within the cylindrical shield or guard 12 is open to the air at the top, as shown in Fig. 1. 65

In order to provide proper vertical support for the shaft 2, said shaft is grooved, as shown at 13 in Fig. 2, at a point above the lower bearing 4, and to this grooved portion of the shaft is adapted a split collar 14, which 70 rests upon the top of the bearing 4, and thus provides vertical support for the shaft.

In like manner the hub of the fan is supported upon the shaft 2 by means of a split collar 15, adapted to a grooved portion 16 75 of said shaft below the hub of the fan.

I claim—

1. The combination in a drying-machine, of a casing having a drying-chamber and a heating-chamber, a shaft leading from the 80 outer side of the casing into the drying-chamber, a fan on said shaft, bearings for the shaft, and a shield extending from the outer side of the casing to the fan and inclosing the shaft and its bearings, substantially as described.

2. The combination in a drying-machine, of a casing having a drying-chamber and an air-heating chamber, a vertical shaft in the upper portion of the drying-chamber, a horizontal fan secured to the lower end of the shaft, and a shield mounted above the fan and protecting the shaft from the heated air, substantially as described. 90

3. The combination in a drying-machine, 95 of a casing having a drying-chamber and an air-heating chamber, a vertical shaft extending through the upper portion of the casing and into the drying-chamber, a horizontal fan mounted on the shaft and having a solid center, bearings for the shaft above the fan, a shield surrounding the shaft and bearings, the space inclosed by the shield being open to the atmosphere at the top and closed by the solid portion of the fan, substantially as described. 100

105

4. The combination in a drying-machine, of a casing having a central drying-chamber and side heating-chambers, said heating-chambers being connected to the drying-chamber, a vertical shaft in the upper portion of the heating-chambers and extending through the casing; a fan secured to the lower portion of the shaft and having a hollow center, a casing mounted between the fan and the outer shell of the drier, of the same

diameter as the solid portion of the fan inclosing the bearings and the shaft, substantially as described.

In testimony whereof I have signed my name to this specification in the presence of 15 two subscribing witnesses.

CHARLES W. SCHWARTZ, JR.
